[57] CLAIM

The ornamental design for a flashlight, as shown and described.

DESCRIPTION

FIG. 1 is a side elevational view of a flashlight showing my new design, the opposite side being a mirror image; FIG. 2 is a top plan view thereof; FIG. 3 is a bottom plan view thereof; FIG. 4 is a front elevational view thereof; FIG. 5 is a rear elevational view thereof; FIG. 6 is a side elevational view of a second embodiment thereof, the second embodiment differs from the first only by a shorter handle;

FIG. 7 is a side elevational view of a third embodiment thereof, the third embodiment differs from the first only by a reduction in size and an attachment hole on the end;

FIG. 8 is a rear elevational view thereof; FIG. 9 is a side elevational view of a fourth embodiment thereof, the fourth embodiment differs from the first only by a reduction in size, an attachment hole on the end, and no elevated switch; FIG. 10 is a rear elevational view thereof; FIG. 11 is a top plan view thereof.
